CORD TREATING DEVICE

Carl D. Hullinger, Northport, N. Y., assignor, by
mesne assignments, to Darworth, Inc., Simsbury, Conn., a corporation of Connecticut

Application March 15, 1945, Serial No. 582,975

2 Claims. (Cl. 21—61)

1

This invention relates to a cord treating device, and more particularly to a device for applying a chemical solution to thread and cord, such as a fish line, for the purpose of rot-proofing and fungus-proofing the same, and which device is also capable of serving as the container in which the chemical is sold and distributed to the user.

As is well known, threads and cords, such as fish lines of any suitable textile fiber, such as silk, nylon, cotton, linen, and the like, which are necessarily exposed to water and moisture, are prone to rotting from mildew and other fungus growths. Such rotting is commonly inhibited or prevented by impregnating the thread or cord with a suitable chemical solution having rot-proofing and fungus-proofing qualities, and this is commonly done by dipping or placing the thread or cord in a pan containing the chemical solution. This method is messy, inefficient and wasteful in requiring the solution to be poured from its original container, and then replaced in it, after use.

I have accordingly devised a container in which the chemical solution may be sold and distributed to the user and which itself contains means whereby the thread or cord may be passed through the solution while held in its original container, and the cord withdrawn, without waste of the solution nor the messiness incident to the present makeshift methods. My device is simple, inexpensive and handy.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Fig. 1 of the drawings is a vertical section of my container in the form in which the chemical solution is ordinarily sold to dealers and users, and

Fig. 2 is a similar view of the same container showing it in use for treating cord passed through the solution while held in the container.

In the drawings 10 represents a bottle or jar of suitable size, preferably of glass, having a neck 11 open at the top. Spiral threads 12 are formed on the exterior sides of the neck 11 to receive a detachable closure cap 13, which may be of metal, plastic or other suitable material. The cap 13

has sides 14 with complementary spiral grooves or indentations 15 formed therein cooperating with the threads 12 on the container neck in the usual manner. Affixed to the inside of said cap 13 in any suitable manner, as by riveting, welding or the like, is a rod 16, preferably of wire, of sufficient length to extend downwardly into the interior of said container 10 well below the normal surface of the solution when the cap 13 is in its container-closing position, as shown in Fig. 1. Rod 16 has an eye 17 at its lower end through which a thread or cord may be passed. A suitable washer 18 of cork, rubber, waxed paper or other suitable material is held within the interior 15 of said cap 13 in the usual manner to prevent leakage of the chemical solution in the container. In this situation, the device serves as a suitable container in which the chemical solution may be sold and distributed to dealer and user, and stored as long as desired.

The top 11 of the container 10 preferably extends upwardly a sufficient distance to provide room for several rows of spiral threads 12, and the sides 14 of the cap 13 likewise extend downwardly over the top 11 to cover said threads 12. Two holes 19 are preferably provided in the upper portion of the sides 14 of the cap 13. The thread or cord 20 is then treated with the chemical solution by unscrewing the cap 13 and passing the cord 20 through one hole 19 in said cap 13 down through eye 17 of rod 16 and up and out through the other hole 19 in said cap. The cap is then partially screwed on to the container 10 sufficiently to clear holes 19 above the top edge of neck 11, and while held in this position the entire thread or cord 20 may be passed through the solution in the container by pulling it. Holes 19 are preferably rounded or smooth-edged to prevent unnecessary wear on the cord. The holes 19, near the top of sides 14 of cap 13, will not permit leakage of the solution from the container 10, when the cap 13 is tightly screwed on to the top 11, because the washer 18 forms a tight closure against the top 11 and prevents all leakage.

But it is to be understood that the holes 19 of cap 13 may be dispensed with entirely, and when cap 13 is unscrewed, the cord 20 may be passed between said cap 13 and the top 11 of the container 10 and then through the eye 17 of rod 16, the rod 16 serving to keep the top 13 on the container 10 sufficiently to permit the thread or cord 20 to be passed through the eye 17 and solution as before.

The device above described provides a simple, inexpensive and convenient container for dis-

tributing rot-proofing and fungus-proofing solutions for threads and cords, such as fishlines, and provides an easy means for treating the thread or cord, without removing the solution from its original container. It is to be understood, of course, that the present device is not limited to containing and distributing rot-proofing and fungus-proofing solutions, but is adapted to any solutions for treating cords for other purposes.

I claim:

1. A container having an open top and adapted to contain a fluid, a detachable closure cap having sides adapted to be screwed on to said top, a rod attached to said cap and extending into the interior of said container when said cap is in its container-closing position, and having an eye upon its lower end through which a cord may be passed.
2. A container having an open top and adapted to contain a fluid, a detachable closure cap hav-

ing sides adapted to be screwed on to said top, a rod attached to said cap and extending into the interior of said container when said cap is in its container closing position, the sides of said cap having holes, and said rod having an eye on its lower end, through which a cord may be continuously passed when said cap is partially unscrewed.

CARL D. HULLINGER.
